UNITED STATES PATENT OFFICE.

JESSE D. POLLOCK, OF CARPENTER, WYOMING.

SAFETY-CRANK FOR INTERNAL-COMBUSTION MOTORS.

1,207,791.

Specification of Letters Patent. Patented Dec. 12, 1916.

Application filed March 7, 1916. Serial No. 82,613.

To all whom it may concern:

Be it known that I, JESSE D. POLLOCK, a citizen of the United States of America, and resident of Carpenter, in the county of Lar-
5 amie and State of Wyoming, have invented certain new and useful Improvements in Safety-Crank for Internal-Combustion Motors, of which the following is a specification.

10 This invention relates to internal combustion motors and particularly to means for cranking said motors.

An object of this invention is to produce a safety engine cranker or starter in which 15 the coupling mechanism is released upon back firing of the motor, thereby automatically insuring against accident and the danger incident to this operation.

20 A further object of this invention is to produce a device of this character which is positive in its operation and of such simple construction as to be readily applied to automobiles now in common use.

25 With the foregoing and other objects in view, the invention consists in the details of construction, and in the arrangement and combination of parts to be hereinafter more fully set forth and claimed.

30 In describing the invention in detail, reference will be had to the accompanying drawings forming part of this specification in which like characters denote corresponding parts in the several views, and in which—

35 Figure 1 illustrates a view in elevation of a fragment of the front of an automobile with the invention applied thereto; Fig. 2 illustrates a top plan view thereof, the casting of the mechanism being in section; Fig. 40 3 illustrates a sectional view on the line 3—3 of Fig. 2; and Fig. 4 illustrates an enlarged detail view of part of the mechanism.

45 In these drawings 5 denotes the crank shaft of an explosive motor, 6 a stub shaft having a recess 7 in its end for the reception of an end of the crank shaft, and 8 illustrates a set screw for coupling the shaft and stub shaft together, although a ratchet connection may here be substituted.

50 A lever or crank 9 is mounted on the shank 10 of a set screw 11, the said screw being threaded in the end of the stub shaft, as shown in Fig. 3. The crank 9 has a handle 13 and the said handle extends through a dog 14, said dog having a nose 15 which engages 55 the teeth 16 of the ratchet wheel 17, which

ratchet wheel is preferably formed integral with the stub shaft 6. An apertured disk or plate 17^a fits on the shaft 6 and the shaft rotates independently of it. Furthermore, the 60 disk has arms 18 to which pawls 19 are pivoted, the said pawls being under the influence of springs 20, which springs serve to hold the pawls in engagement with the teeth 21 of a ratchet wheel 22, which ratchet wheel is mounted on the shaft 6. The ratchet wheel 22 has an arm 23 from which a pin 24 extends, the said pin lying in a slot 25 of the dog 14. The purpose of this arrangement is to effect a disengagement of the dog 70 from the ratchet wheel 17 should there be a back fire in the motor. When the crank is rotated, the dog engages the teeth of the ratchet wheel 17, thus communicating motion to the crank shaft of the motor. On 75 the clock-wise movement of the crank shaft, the dog travels a slight distance, that is to say a distance equal to the length of the slot 25 before the pin 24 strikes the wall of the outer end of the slot and when this occurs, 80 the ratchet wheel 22 is rotated in a clock-wise direction so long as the parts are normally operated. Should there be a back fire however, the dogs 19 would engage the ratchet wheel 22 and arrest the movement of 85 said ratchet wheel since the said ratchet wheel is loose on the stub shaft 6. When the ratchet wheel 22 comes to rest, the dog would of course move longitudinally on the pin 24 and as the pin is in a diagonal 90 slot of the dog, the action of the pin would be to disengage the nose of the dog from the ratchet wheel 17, thus freeing the said ratchet wheel to permit the motor to run backward without further communicating 95 motion to the crank shaft.

The plate 17^a is held stationary by means of a rod 27 which extends from one of the arms 18 to a staple or other anchorage 28. Furthermore, a spring 29 is connected to 100 the arm 23 and to the pawl so that the said pawl is held normally out of engagement with the ratchet wheel thereby.

I claim—

1. In a safety motor crank, a shaft, a 105 ratchet wheel thereon, a dog adapted to engage the ratchet wheel, means for supporting the dog whereby it may rotate the shaft in one direction, a ratchet wheel rotatable on the said shaft, an arm thereon having 110 a pin, said dog having a cam slot to receive the pin, the said dog being slidable with re-

lation to the pin, means for holding the dog normally out of engagement with the ratchet wheel, and a stationary member having dogs for engaging the second mentioned ratchet wheel to prevent anti-clockwise movement thereof upon back fire of the motor.

2. In a safety motor crank, a crank shaft having a ratchet wheel thereon, a dog for 10 engaging said ratchet wheel, said dog having a cam slot, a ratchet wheel rotatable on the said shaft and having a pin extending through the said cam slot, and means for preventing anti-clockwise motion of the second mentioned ratchet wheel.

3. In a safety motor crank, a crank shaft, a ratchet wheel thereon, an arm rotatable with relation to the shaft, a dog connected

to the said arm and moving therewith, said dog having a slot in its inner end, a ratchet 20 wheel rotatable on the shaft, a pin projecting from said ratchet wheel into the slot of the dog, a plate on the said shaft, said plate having arms, pawls pivoted on said arms and adapted to engage the second mentioned 25 ratchet wheel to prevent anti-clockwise rotation of the said ratchet wheel, and means for holding the dog normally out of engagement with the ratchet wheel.

In testimony whereof, I affix my signature 30 in the presence of two witnesses.

JESSE D. POLLOCK.
